UNITED STATES PATENT OFFICE

ADOLF A. WIDMANN, OF DETROIT, MICHIGAN, ASSIGNOR TO HERMANN I. A. DORNER,
OF DETROIT, MICHIGAN

INTERNAL COMBUSTION ENGINE

Application filed October 10, 1931. Serial No. 568,170.

This invention relates to apparatus for starting internal combustion engines, and more particularly to engines employing ignition means of the incandescent type, commonly referred to as glow plugs.

Difficulty has heretofore been encountered in the design of glow plugs to enable them to function properly for a longer period than a few hours. It has been found that the high temperature to which the incandescent element must be raised, this temperature being increased by the heat of the engine, together with the excessive vibration induced in the incandescent element by the motor explosions and other regular impulses result in the rapid deterioration and breakage of the element.

The glow plug has nevertheless been found extremely useful in internal combustion engines of the compression ignition type, since a separate igniter is required only during starting of the engine and thus an ignition device which is capable of use for only a few hours will serve the purpose. Furthermore, it is found that in engines operating on the Diesel cycle and burning fuel oil, the spark plug fails to give sufficient heat and to distribute that heat over a sufficiently wide area to ensure proper ignition of the cold fuel mixture in starting the engine.

Thus it is important to conserve the life of the incandescent element by ensuring that this element will be energized for a short period of time only when starting the engine in order to lengthen the life both of the plugs and the battery by means of which they are energized. This may, of course, be taken care of by the operator when a separate switch is provided for energizing the glow plugs, but it is preferable to eliminate the personal element and to ensure that the plugs will be energized for a predetermined period only each time the engine is started.

It is furthermore found desirable to maintain the ignition means in operation for a brief interval of time after rotation of the engine has been initiated by the starter and the firing of the combustible mixture has commenced since this mixture is still rela-

tively cold and stalling of the engine after the starter has ceased to function may result.

It is therefore an object of the present invention to provide time controlled means for determining the period during which the ignition means remains active at each starting operation.

A more specific object of the invention is the provision of means whereby the starter and the ignition means may be simultaneously energized and whereby the duration of energization of the ignition means is determined independently of the means which initiates the energization thereof.

A further object of the invention is the provision of a single switch for rendering the starter and ignition means simultaneously operative and time controlled mechanism for thereafter rendering the ignition means inoperative.

Preferably the arrangement is such that relay elements may serve for the control of the main circuits supplying current to the starter and the ignition means since both starters and ignition means of the incandescent type require a relatively heavy current. It is thus possible to avoid the premature burning out of the contact-making devices in the circuit.

It is a further object of the invention to provide means whereby the length of time of energization of the plugs will be materially reduced when the engine is warm, for instance when it is found necessary to stop and restart the engine. In this way the life of the plugs and the battery may be lengthened.

Further objects and features of the invention will be apparent from the following description taken in connection with the accompanying drawing, in which

Figure 1 is a diagrammatic illustration of one arrangement of electrical circuits for controlling a starter and ignition means in accordance with the principles of the invention; and

Figure 2 is a similar diagrammatic illustration disclosing a modification of the arrangement shown in Figure 1.

Referring more specifically to Figure 1 of the drawing, it will be observed that a source of current supply 10, preferably a battery having one pole grounded as shown, serves to energize the starter 11 and the ignition means 12. A current controlled switch or relay 15 is interposed between the other pole of the battery and the starter 11 and a second current controlled switch 16 is interposed between the battery and the ignition means 12.

- 10 The opposite lead from the starter is grounded on the engine or engine support at 17 and the ignition means, which in the preferred form of the invention, are of the incandescent or glow plug type, are grounded at 18 in the conventional manner. Thus when the current controlled switches 15 and 16 are closed, a heavy current will flow through the starter 11 and the glow plugs 12.
- 20 A starter switch 19, consisting of a movable contact arm 20 and fixed contacts 21 and 22 is provided, the movable contact being grounded as indicated at 25 and being arranged to engage the fixed contacts in the closed position of the switch.

25 The fixed contact 21 is connected through the winding 26 to the battery 10 and thus when this contact is grounded by closing the starter switch, the relay is energized to bridge the contacts 28, 29 in the main starter circuit for operating the starter. It will be observed that the control circuit for the starter is entirely independent of the circuits which control the ignition means.

- 30 35 The main circuit for the ignition means comprises the fixed contacts 31, 32 which are arranged to be bridged by the movable contact 33 when the relay 16 is operated by energizing the winding 35. One side of this winding is connected to a pair of fixed contacts 34 associated with a movable contact 36 normally engaging a fixed contact 37 and movable into engagement with a second fixed contact 38 on actuation of the relay. The 40 fixed contact 37 is connected to the fixed contact 22 of the starter switch and fixed contact 38 is grounded preferably by connection to the movable contact 20 of the starter switch. The other side of the winding 35 45 of the relay 16 is connected to the fixed contact 40 of a time controlled switch 41, preferably of the thermostatic type, this contact normally engaging the movable contact 43 of the switch which is mounted on and electrically connected with a bi-metallic element 45 having one end thereof rigidly mounted at 46, the bi-metallic element being in turn connected to the battery 10 as indicated at 50 49. It will be understood that the difference in coefficients of expansion of the two metals of which the element 45 is formed is utilized to separate the contacts 43 and 40 when the element 45 reaches a predetermined temperature as a result of the energization of the

heating coil 48. The heating coil 48 surrounds the bi-metallic element and is connected at one end thereto, the other end being connected to the winding 35 of the relay 16 so that this winding and the heating coil are initially arranged in parallel in the circuit between the starter switch and the battery.

55 It will now be observed that when the starter switch is closed the fixed contact 22 of the switch is grounded and current flows through the contacts 36 and 37 and through the winding 35 of the relay 16 and the heating coil 48 of the time controlled switch to the battery. Thus the relay 16 is energized, 60 the contacts 31 and 32 of the main circuit of the ignition means are bridged and simultaneously the movable contact 36 is shifted from engagement with the contact 37 to the contact 38, the circuit including the winding 65 of the relay 16 being thereby again grounded by a by-pass around the starter switch. Thus if the starter switch is opened, the relay 16 will remain energized and the main circuit for the ignition means will remain 70 closed, although operation of the starter has been discontinued. When the bi-metallic element 45 has been sufficiently heated by the coil 48, the contacts 43 and 40 will separate and the circuit controlling the relay 16 will 75 be opened, thus permitting the relay to assume its original position with the main ignition circuit opened.

80 In this manner the ignition means are automatically controlled so as to supply heat 100 to the cylinder for a predetermined period of time, this period being preferably longer than that normally required for the starting of the engine.

85 By reason of the high degree of compression it is ordinarily preferable to start Diesel 105 motors by storing up the energy of the starter motor in a fly-wheel which is clutched to the engine after being brought to the proper speed. It will nevertheless be observed that 110 the present arrangement is applicable regardless of whether the centrifugal type of starter is used or whether the starter motor is connected directly to the engine.

90 Referring now to Figure 2 of the drawing, in which similar reference numerals have been used to indicate similar parts, it will be observed that the starter 11 and glow plugs 12 are arranged to be connected to the same side of the source of current supply 10, the opposite side of this source being grounded as indicated at 70. Two relays or current controlled switches 72 and 73 are provided, the latter being a retarded relay, for a purpose hereinafter described. The starter 120 switch 75 is of the double pole type, one movable contact 76 being connected through the lead 78 to the winding for the relay 72 and thence to the ground 80 for the starter. The other lead from the starter is connected to 125

one of a pair of fixed contacts 81, 82, the other contact being connected to the current source 10, which are arranged to be bridged by the movable contact 84 of the relay 72. Thus, closing of the starter switch 76 energizes the relay 72 to supply current to the starter 11. The source of current supply 10 is also connected by a lead 85 to one of a pair of fixed contacts 87, 88 which are arranged to be bridged by a movable contact 90 of the relay 73 to supply current to the glow plugs 12. The remaining movable contact 92 of the double pole switch 75 is connected to one end of the winding of the relay 73, the other end of this winding being grounded, as indicated at 94. The closing of the starter switch 75 therefore completes the circuit through the lead 85 to the glow plugs 12 which remain ignited as long as the winding 20 of the relay 73 is energized.

If the starter switch 75 is now opened, the winding of the relay 72 will be de-energized, permitting the movable contact 95 to move to the position shown in Figure 2 bridging the contacts 96, 97, one of which is connected to the source of supply 10 and the other of which is connected through a time controlled switch indicated generally at 41 to a fixed contact 98. A fixed contact 99, connected to the movable arm 92 of the starter switch and to one end of the winding for the relay 73 is arranged to be connected by a movable contact 101 of the relay to the fixed contact 98. Current will then flow from the source of supply 30 through the contacts 96, 95, 97 and through the time controlled switch 41 and the contacts 98, 101 and 99 to the winding for the relay 73 and thence to the ground 94. It will be observed that although the starter switch 75 has 40 been opened, an auxiliary circuit has been established supplying current to the winding of the relay 73 so that this relay is maintained in such position that the contacts 87 and 88 are bridged by the movable contact 90 and thus 45 the glow plugs 12 remain energized.

As mentioned hereinbefore, the relay 73 is of the retarded type, this being necessary in order that the bridging of the contacts 96 and 97 on deenergization of the relay 72 may be completed before the circuit, including the contacts 87 and 88, has been opened by the de-energization of the relay 73. Thus the auxiliary circuit through the time controlled thermostat 41 is brought into operation before the relay 73 has moved to open the contacts 87 and 88.

The passage of current through the time controlled element functions in the manner described in connection with the similar element shown in Figure 1 to open the circuit energizing the relay 73 after a predetermined period of time and thus the glow plugs remain hot after the operation of the starter has been discontinued regardless of the length 60 of time of operation of the starter.

It may be found desirable to reduce the period of operation of the ignition means when the engine is hot to further prolong the life of the glow plugs and the source of supply. This may be done by fitting the time controlled element 41 in a suitable casing 104 and inserting this casing in a recess 105 in the cylinder wall or cylinder head 107. So long as the temperature of the motor is sufficiently high to ensure combustion, the bimetallic element 45 of the thermostat 41 will be deflected to maintain the contacts 40 and 43 out of engagement and the relay 73 will be operated only during operation of the starter and the plugs will cease to glow as soon as the starter switch is open, the time controlled device for extending the period of operation of the plugs being thus rendered inoperative.

This arrangement may also be provided in the circuit shown in Figure 1, in which event 85 the ignition means will not be energized at all if the motor is hot.

It will be observed that in this modified form the ignition means will always be active during operation of the starter and during this period is entirely independent of the thermostatic control.

It will be appreciated that the foregoing detailed description of the invention has been given to facilitate an understanding of the inventive principles as embodied in the particular arrangement shown in the drawing and that such modification of the elements shown and described herein are contemplated as fall within the spirit and scope of 95 the appended claims.

Having thus described the invention, what is claimed as new and desired to be secured by Letters Patent is:

1. In an internal combustion engine, the combination with an engine starter, of a source of electric current, means including a starter switch associated with said source and starter for energizing said starter when the switch is operated, fuel ignition means associated with said engine, means for supplying current to said fuel ignition means when the starter switch is operated, and time-controlled means for rendering said last named means inoperative.

2. In an internal combustion engine, the combination with means for driving said engine for starting purposes, of an electrical circuit including a source of supply for energizing said engine driving means, control means for rendering said circuit operative or inoperative, a device for supplying heat to the combustible fuel mixture, and time-controlled means associated with said electrical circuit and said device and rendered operative when said engine driving means is energized for maintaining said device in operation for a predetermined time.

3. In an internal combustion engine, the combination with an engine starter, of means

for supplying current to said starter, said means including a switch, means for supplying heat to the combustible mixture for starting, a time-controlled relay for controlling said last named means, and connections between said switch and relay for initiating operation of the latter.

4. In a Diesel engine, the combination with an engine starter, of ignition means of the incandescent type for supplying heat to said engine for starting, starter control means movable to a position for energizing said starter, means operable by said starter control means on movement of the latter to such position for supplying current to said ignition means, and means acting independently of said starter control means to automatically interrupt the supply of current to said ignition means after an interval of time.

5. In an internal combustion, compression ignition engine, the combination with an engine starter, of fuel ignition means of the incandescent type for use in starting, a single switch for rendering said starter and ignition means operative, and time controlled means acting independently of said switch for thereafter maintaining said ignition means operative for a predetermined period of time.

6. In an internal combustion engine, the combination with an engine starter, of a relay for controlling operation of said starter, fuel ignition means of the incandescent type, a relay for controlling operation of said ignition means, a switch for energizing both of said relays, and time controlled means for maintaining energization of said second named relay for a predetermined interval of time.

7. In an internal combustion engine, the combination with an electrically operated engine starter, of fuel ignition means of the incandescent type, a source of current supply, a circuit including said source and starter and a circuit including said source and ignition means, current controlled means in each circuit for opening and closing said circuits, a main switch for controlling the supply of current to said current controlled means, an auxiliary circuit including a time controlled element for supplying current to the current controlled means in the circuit for said ignition means, and means for rendering said auxiliary circuit active when said main switch is closed.

8. In an internal combustion engine, the combination with an electrically operated engine starter, of fuel ignition means of the incandescent type, a source of current supply, a circuit including said source and starter and a circuit including said source and ignition means, current controlled means in each circuit for opening and closing said circuits, a main switch for controlling the supply of current to said current controlled means, an auxiliary circuit including a time controlled

element for supplying current to the current controlled means in the circuit for said ignition means, and means for rendering said auxiliary circuit active when said main switch is opened to open said starter circuit, whereby said ignition means will remain energized for a period of time thereafter.

9. In an internal combustion engine, the combination with an electrically operated engine starter, of fuel ignition means of the incandescent type, a source of current supply, a relay for said starter, a relay for said ignition means, a switch for energizing said relays, time controlled means bypassing said switch for energizing said ignition relay, and means operable by said switch for rendering said time controlled means operative.

10. In an internal combustion engine, the combination with an engine starter, of means for supplying current to said starter, said means including a switch, means for supplying heat to the combustible mixture for starting, a time-controlled relay for controlling said last named means, and connections between said switch and relay for initiating operation of the latter, and means whereby said time-controlled relay is rendered inoperative when the engine temperature is sufficiently high for starting purposes.

11. In an internal combustion engine, the combination with an engine starter, of a relay for controlling operation of said starter, fuel ignition means of the incandescent type, a relay for controlling operation of said ignition means, a switch for energizing both of said relays, means for maintaining energization of said second named relay for a predetermined interval of time, and means whereby said last named means is rendered inoperative when the engine temperature is sufficiently high for starting purposes.

12. In an internal combustion engine, the combination with an engine starter, of a source of electric current, means including a starter switch associated with said source and starter for energizing said starter when the switch is operated, fuel ignition means associated with said engine, means for supplying current to said fuel ignition means when the starter switch is operated, and time-controlled means for maintaining the supply of current to said ignition means, said time-controlled means being positioned so as to be subjected to heat developed by said engine and including a heat responsive switch and a heating coil operatively associated with the heat responsive switch.

13. In an internal combustion engine, the combination with fuel ignition means of the incandescent type, of means for energizing said fuel ignition means for starting purposes, and time controlled mechanism associated with said last named means for terminating the energization of said last named means.

14. In an internal combustion engine, the combination with fuel ignition means of the continuously operated incandescent type, of an electrical circuit including a source of supply for energizing said means for starting purposes, and a thermostatic element included in said circuit and operable in response to a temperature change for opening the said circuit.

15. In an internal combustion engine, the combination with fuel ignition means of the continuously operated incandescent type, of an electrical circuit including a source of supply for energizing said means for starting purposes, and a thermostatic element included in said circuit and operable in response to a temperature change for opening the said circuit, said thermostatic element being heated by electrical energy flowing in said circuit.

16. In an internal combustion engine, the combination with fuel ignition means of the continuously operated incandescent type, of an electrical circuit including a source of supply for energizing said means for starting purposes, and a thermostatic element included in said circuit and operable in response to a temperature change for opening the said circuit, said thermostatic device being so positioned as to receive heat from the engine for operation thereof.
